AUTOMOBILE GRILLE

Paul E. Milliken, 18 Hurlburt Ave., Akron, Ohio

Filed June 20, 1962, Ser. No. 70,630

Term of patent 14 years

(Cl. D14—18)

FIG. 1 is a front elevational view of an automobile grille showing my new design; and

FIG. 2 is an enlarged sectional view taken at line 2—2 of FIG. 1.

The essential features of the design reside in the portions shown in full lines.

I claim:

The ornamental design for an automobile grille, as shown and described.
